COMBINED BOTTLE AND CAN OPENER

Andrew D. Hall, David's Hill Road,
Bedford Hills, N.Y. 10507

Filed Oct. 24, 1974, Ser. No. 517,735

Term of patent 14 years

Int. Cl. D7—99

U.S. Cl. D8—38

FIG. 1

FIG. 3

FIG. 2

FIG. 4

FIG. 6

FIG. 5

FIG. 7

FIG. 1 is a front perspective view of a combined bottle and can opener showing my new design;

FIG. 2 is a front elevation thereof;

FIG. 3 is a right end elevation of FIG. 2;

FIG. 4 is a top plan view thereof;

FIG. 5 is a bottom plan view thereof;

FIG. 6 is a left end elevation of FIG. 2; and

FIG. 7 is a front perspective view with the opener rotated in a second position.

I claim:

The ornamental design for a combined bottle and can opener, substantially as shown and described.
